(57) **CLAIM**

The ornamental design for a paint can accessory, as shown and described.

DESCRIPTION

FIG. 1 is a top view of a paint can accessory showing my new design.

FIG. 2 is a left side elevation view thereof. The right side is a mirror image of FIG. 2; and,

FIG. 3 is a bottom view thereof.

In the drawings, the broken lines depict environmental subject matter only that forms no part of the claim.
